UNITED STATES PATENT OFFICE.

CARL H. RICHTER, OF CHICAGO, ILLINOIS, ASSIGNOR TO RICHTER MANUFACTURING COMPANY, OF CHICAGO, ILLINOIS, A CORPORATION OF ILLINOIS.

BANJO AND THE LIKE.

Application filed December 12, 1925. Serial No. 74,966.

This invention relates to improvements in banjos and the like and it consists of the matters hereinafter described and more particularly pointed out in the appended claims.

The main objects of the present invention are to improve and simplify the construction of the body or shell and the parts associated therewith, of a banjo or similar instrument, so that the instrument will not only be more durable in construction and lighter in weight, but will be more attractive in appearance and capable of being produced at a greatly reduced cost.

These objects of the invention, as well as others together with the many advantages thereof, will more fully appear as I proceed with my specification.

In the drawings:—

Fig. 1 is a top plan view of the shell end of a banjo or similar instrument, embodying my invention.

Fig. 2 is a view in side elevation of the same.

Fig. 3 is a vertical section through one side of the shell on an enlarged scale as taken on the line 3—3 of Fig. 1.

Fig. 4 is detail view in elevation of the tail piece of the banjo or similar instrument.

Referring now in detail to that embodiment of the invention illustrated in the accompanying drawing, 1 indicates as a whole the shell or body of a banjo or like instrument and 2 indicates the neck thereof. As shown herein said shell is made of a light gauge strip of metal, rolled into the form of a ring or annulus and includes an upright side wall 3 of the same diameter throughout. The top marginal portion of the shell is turned over at a right angle to form an inwardly extending top flange 4 joined to said wall by a rounded corner 5 as best shown in Fig. 3, so as to present no sharp corners to the head skin or vellum later to be described. The bottom marginal portion of the shell is turned inwardly and slightly upwardly as best shown in said Fig. 3 so as to provide a rounded bottom edge like flange 6 for the shell which cannot catch upon the clothing of the person playing the instrument or in no manner mar the finish of a table or like surface upon which the instrument may be placed.

Said shell is also formed to provide an integral outwardly extending flat bracket 55 flange 7 of a double thickness of metal ar-

ranged nearer the bottom edge of the shell than the top edge. In said flange which is formed of a double thickness of metal, is provided a plurality of arcuately spaced openings 7^a, only one of which is shown in Fig. 3. A shell made as described, although formed of thin sheet metal, is light in weight, and is strong and rigid and will not warp nor can it be easily bent out of shape due to the rough handling to which it may sometimes be subjected.

8 indicates the head for the instrument which may be made of skin or vellum as is usual in instruments of this kind. The peripheral margin of said head is suitably secured to a flesh ring or hoop 9 of a diameter to snugly fit over the top end of the shell. Associated with said head is a strain ring or hoop 10. Said hoop is made of a flat metallic band in the form of a ring or annulus and is adapted to engage at its bottom edge with the flesh ring or hoop, the top edge of said hoop projecting a suitable distance above the plane of the head 8. Brackets are provided for drawing the strain hoop 10 downwardly toward the flange or rib 7 to impose the desired tautness upon the head, the number of brackets employed, of course depending upon the diametric size of the shell or body. Each bracket includes a cylindrical and threaded shank 11 and a somewhat flattened top part 12, the free end of which is bent over to provide a hook to engage the top edge of the strain hoop. The threaded bottom end of the shank of each bracket, extends through and beyond an associated opening 7^a in the shell flange 7 and threaded onto each shank end from below the flange is the usual adjustment nut 13. In tightening up the nuts which abut said flange the brackets act to draw the strain hoop downwardly and as said hoop engages the flesh ring 9, the head may be drawn taut to the desired degree. In this movement of the strain hoop and flesh ring, the head is drawn down over the rounded corner 5 of the shell, which in no manner acts to cut or otherwise injure the skin or vellum of the head.

The neck includes a butt portion 14 of a depth greater than the main body portion and the end of said butt portion is rounded concavely to fit against the shell as best shown in Figs. 1 and 2. In said concaved end of the butt near the top surface of the

neck is formed a groove 15 to receive the flesh ring 9 and said groove is of a height greater than the flesh ring to accommodate the movement thereof under the action of 5 tightening up the brackets. Below said groove is another groove 16 in which the flange 7 of the shell snugly fits as shown in Fig. 3. Integral with the butt is a longitudinal extension 17 which projects 10 through a suitable opening in the shell and extends diametrically across the same, a screw 18 being inserted through the shell from the outside and threaded into the end 15 of said extension thus securely affixing the shell and neck together. The top surface of the neck which is flat has the usual fret bars 19.

On that part of the shell diametrically opposite the neck is a tail piece indicated by 20 the numeral 20 as a whole. Said tail piece is of an inverted L shape and includes a horizontal part 21 and vertical part 22. 23 indicates the various strings of the instrument, the rear ends of which pass under the 25 tail piece part 21 to be suitably anchored in the vertical part of the tail piece as best shown in Figs. 2 and 4. Said strings pass over a bridge 24 supported on the head and then extend over the top surface of the neck 30 and above the fret bars 19 thereon to be attached to the usual tuning pins not herein shown. The top marginal portion of the strain hoop 10 is cut away as at 10^a for the 35 passage of the strings.

35 In the bottom end of the vertical part of the tail piece is formed a key hole shaped opening to receive the head on the top end of a tension bolt 26, the bottom end of which passes through the shell flange 7 and has a 40 nut 27 threaded thereon below said flange. By tightening up on said nut, the tail piece may be tightly but removably secured in place upon the shell.

45 My improved construction has many advantages. Although light in weight the shell thereof is of such rigidity as will amply resist the strains imposed upon it without warping or bending out of shape. The shell may be more economically made and is not only attractive in appearance but is so formed as to present no sharp corner to the skin or vellum head and no sharp corners to catch upon the clothing of the person playing the same. The improved construction 50 is applicable to banjo-ukes, tenor-banjos and mandolin-banjos so that the description of the invention herein is to be so taken as to include all of said instruments.

60 A further and particular advantage of my improved construction resides in the fact that there is a distinct improvement in the tone of the instrument. This is a musical instrument and of course the tone quality is of prime importance. Should any device 65 which may become loose be embodied in an

instrument of this character, counter vibrations are set up in the playing of the instrument so that the tone is necessarily affected adversely. This is exactly what I find has obtained in an instrument of this kind heretofore devised and by actual test with my device I find that the construction does actually improve the tone. As before stated my shell is of one piece construction and the flange "7" of the shell is so formed and constructed that it is extremely rigid in character and not subject to be set in vibration when the instrument is in use. 70

75 While in describing my invention, I have referred to many details of mechanical construction as well as form and arrangement of the parts thereof, the same is for the purpose of illustration only, so that I do not wish to be limited thereto except as may be pointed out in the appended claims. 80

85 I claim as my invention:

1. An instrument of the kind described embodying therein a thin sheet metal shell formed to provide an integral flat bracket flange thereon of a double thickness of metal, 90 a head including a flesh ring, fitted upon one end of the shell, a strain hoop engaged with said flesh ring and a part of said head and brackets engaged with said strain hoop and flange respectively and means to adjusting said brackets. 95

2. An instrument of the kind described embodying therein a thin sheet metal shell formed to provide an integral flat bracket flange thereon of a double thickness of metal, 100 a head including a flesh ring, fitted upon one end of the shell, a strain hoop engaged with said flesh ring and part of said head and brackets having a hooked engagement at one end with said strain hoop and extending at their other ends through and beyond said flat flange and nuts threaded on said brackets below and in engagement with said flange. 105

3. An instrument of the kind described 110 embodying therein, a thin sheet metal shell formed with an inwardly extending integral flange at its top end and with an outwardly extending integral flat flange of a double thickness of metal below said top 115 end, a head including a flesh ring fitting upon said top end with the head in engagement with said inwardly extending top flange and with the flesh ring below the same, a strain hoop seated upon the flesh 120 ring and brackets having a hooked engagement at one end with said strain hoop and extending through and beyond said flat flange and nuts threaded upon said brackets below and in engagement with said flat 125 flange.

4. An instrument of the kind described 130 embodying therein, a thin sheet metal shell formed with an inwardly extending integral flange at its top end and with an outwardly

- extending integral flat flange of double thickness below the said top end, a head including a flesh ring fitting upon said top end of said shell and with the head in engagement with said inwardly extending flange and with the flesh ring below the same, a strain hoop seated upon the flesh ring and brackets operatively engaged at one end with the strain hoop and at the other end with said outwardly extending flat flange of double thickness, and nuts associated with said brackets engaging the last mentioned flange and providing adjustment of said brackets.
- 5 5. An instrument of the kind described, embodying therein, a thin sheet metal shell formed with inwardly extending flanges at the top and bottom ends thereof, and an outwardly extending integral flat flange of a double thickness of metal between said top and bottom ends, a head including a flesh ring fitting upon said top end with the head in engagement with the inturned flange
- 10 at the top end of the shell and with the flesh ring below the same, a strain hoop seated on the flesh ring, brackets having their top ends hooked over said strain hoop and having their bottom ends extending through and beyond said outwardly extending integral flat flange and nuts threaded on said last mentioned ends of the brackets and engaging against the underside of said last mentioned flange.
- 15 6. A shell for an instrument of the kind described embodying therein a thin sheet metal endless ring having inwardly extending flanges at its top and bottom ends and an outwardly extending flat flange of double thickness, between said ends, said last mentioned flange having arcuately spaced openings therein for the brackets usually associated therewith.
- 20 In testimony whereof, I have hereunto set my hand, this 25th day of November, 1925.

CARL H. RICHTER.
